OIL CLEANER

Application filed May 31, 1930. Serial No. 458,279.

This invention relates generally to the class of separators, and refers more particularly to a fluid cleaner which, while not necessarily restricted to such use, is especially designed for the purpose of continuously cleaning lubricating oil as it leaves the pump and is circulated thereby from the crank case of a motor to the bearings and other parts being lubricated.

10 Broadly, the invention comprehends an oil cleaner of the indicated character, in which the separation of grit or other solid foreign matter, as well as heavier, liquids, such as water, is accomplished by centrifugal force.

The invention in its principal use aims as a further object to provide an oil cleaner for an internal combustion motor, which is preferably installed at a convenient point between the pump outlet and the bearings or other parts to be lubricated, and in which the rotating parts of said cleaner are preferably driven by a moving part of the motor.

20 More specifically, the invention resides in the provision of an oil cleaner having a settling basin, in which the foreign matter separated by the cleaner is gravitationally collected, and which settling basin is disposed below and communicates with the bottom of the crank case or oil reservoir of the motor, whereby periodical draining of said crank case or reservoir may be effected through the settling basin to flush out the said settling basin in order to remove therefrom the foreign matter collected therein.

25 Other objects of the invention reside in the provision of a highly efficient separator or fluid cleaner which employs few and simple parts, which may be economically produced and assembled, and which device may be readily installed or removed for the purpose of repair and cleaning.

With the above recited and other objects in view, reference is had to the following description and accompanying drawings, in which there is exhibited one example or embodiment of the invention, while the claims define the actual scope of the same.

30 In the drawings:

Figure 1 is a vertical longitudinal section-

al view through the cleaner illustrating the same applied to the crank case of a motor.

Figure 2 is a fragmentary vertical sectional view therethrough taken approximately in the plane indicated at 2-2 in Figure 1.

Figure 3 is a face view of one of the separator disks.

As illustrated in Figure 1 of the drawings, the device is shown in its principal use in connection with an internal combustion motor, as an oil cleaner. The device includes a casing having an upper hollow cylindrical portion 10 having an open side which is normally closed by a closure plate 11 removably secured in place in any desired manner, such as by bolts or other equivalent fastening elements 12. The portion 10 and closure plate 11 define a substantially flat circular upper chamber, the axis of which is disposed in a substantially horizontal plane. The upper portion 10 is provided with a depending tubular neck 13 which communicates therewith and terminates at its lower end in a suitably sized and shaped settling basin 14. The lower end of the settling basin 14 is provided with a removable closure plug 15 equipped with a drain cock 15a.

The device further includes a plurality of spaced parallel connected members 16, which are preferably in the nature of disks or circular plates provided with slightly spaced thickened peripheries 17, and each of which is formed with a concentric circular series of apertures 18 disposed axially thereof and defining fluid passages therethrough.

80 Preferably, the plates or disks 16 are secured together and spaced from each other by means of circumferentially spaced bolts 19 which extend through the plates or disks 16, and spacing sleeves interposed between the adjacent pairs of plates or disks. The intermediate disks and one of the end or outermost disks 16 are provided with aligned central apertures or fluid passages 21, while the remaining end or outermost disk, namely, 85 the one at the left, is non-apertured and is secured to an outwardly projecting concentrically arranged axially disposed stub shaft 22 which extends through a packing gland or stuffing box 23 on the outer side wall of the 100

portion 10 of the casing and is journaled therein for rotation, whereby the disk or plate assembly is mounted for rotation within the circular chamber. The protruding portion of the shaft 22 is driven in any suitable manner, preferably from the motor, and, as illustrated, a driving pulley or shaft 24 is secured to the protruding portion of the stub shaft 22, whereby a belt or other equivalent connection is trained therearound and around a rotating part of the motor.

In order to provide means for introducing the oil or other fluid to the casing, one side wall, preferably, the left side as illustrated in Figure 1, is provided with an intake nipple 25, with which a conduit 26 is coupled or joined, which conduit leads from the outlet of the oil circulating pump A, the intake of which oil pump as commonly used in internal combustion motors, communicates with the sump portion of the crank case 27 of the motor by a conduit B. In order to convey off the fluid or lubricating oil from the container, a conduit pipe 28 leading to the bearings or other parts to be lubricated extends concentrically through the closure plate 11 of the casing and preferably projects into the central aperture of the centrally apertured right end plate. While, of course, the device may be supported in any suitable manner, as illustrated the conduit pipe 28 also serves in the capacity of a bracket for supporting the device by extending the same through the side wall of the crank case and securing the same to the crank case.

In use and operation of the device, the lubricating oil of the motor as it leaves the oil pump and is circulated thereby from the crank case of the motor, is led by the conduit 26 to the eccentrically disposed intake nipple 25, thence through the nipple to the cleaner casing 10, where it enters at a point substantially in registry with the orbit of the passages or apertures 18 in the plates or disks 16. As the disks or plates are rapidly rotated by the driving of the shaft 22, the lubricating oil or other fluid is fed between the plates and rotated thereby and therewith, at the same time being forced by the pump pressure through the passages 18 and 21. Obviously, particles of solid matter or liquids, such as water, which are heavier than the lubricating oil, will be thrown off radially by centrifugal force between the thickened peripheries 17, to rid the oil as it moves through the passages 18 and 21, of said heavier solid and liquid matter, so that the cleaned oil eventually finds its way out through the concentrically disposed conduit 28 where it is fed to the bearings or other parts to be lubricated, in a cleaned condition. The thickened peripheries 17 restrict the outlet space at the outer edge of the plates and retard the radial outward movement of the oil while allowing the heavier solid or liquid matter to be more readily discharged. At the

same time, the heavier particles of solid matter or liquids gravitate from the upper portion 10 of the casing through the depending neck 13, where they are collected in the settling basin 14 for subsequent removal. Due to the fact that a considerable quantity of water is collected in the settling basin, it is essential in the colder climates and in the winter time, to frequently draw off the water to prevent freezing of the same and possible bursting of the settling basin structure. For this reason, the drain cock 15a is provided, which may be opened at desired periods to particularly rid the settling basin of water collected therein.

In practice, the settling basin will be disposed below the sump portion of the crank case 27, as clearly illustrated in Figure 1 of the drawings, and a conduit 29 establishes communication between the bottom of the crank case sump portion or other oil reservoir and the settling basin, whereby the periodical draining of the crank case or reservoir may be effected through the settling basin by removing the closure plug 15. This permits the drained off oil to flush out the settling basin for the purpose of removing therefrom the foreign matter collected therein. In order to prevent possible forcing under the pump pressure of matter collected therein through the conduit 29 into the sump portion, a check valve 30 is arranged in the conduit 29. It is also apparent that when necessary the device may be completely disassembled so that the interior of the casing 10 and settling basin, as well as the plates or disks, may be scraped and cleaned to remove therefrom foreign matter which adheres to the surfaces thereof.

While the device has been disclosed as preferably working on a substantially horizontal axis, it is to be distinctly understood that the same is not necessarily restricted thereto, and, if desired, may be disposed on a substantially vertical axis, in which instance, it is, of course appreciated that the settling basin will be disposed below the separator chamber.

While there has been illustrated and described a single and preferred embodiment of the invention, no limitation is intended to the precise structural details, as it is to be clearly understood that variations and modifications which fall within the scope of the invention may be resorted to when desired.

What is claimed is:

1. An oil cleaner including a plurality of spaced parallel apertured plates mounted for rapid rotation on a substantially horizontal axis, a stationary casing enclosing said plates having an eccentric oil inlet and a concentric oil outlet, and a settling basin communicating with the lower end of and disposed below said casing.

2. An oil cleaner including a plurality of spaced parallel plates, said plates having cir-

- 5 cumferentially spaced axially disposed oil passages, the intermediate and one of the outer end plates each being centrally aper- tured, said plates mounted for rapid rotation on a substantially horizontal axis, a station- 6 ary casing enclosing said plates having an eccentric oil inlet adjacent the non-centrally apertured end plate and having a concentric oil outlet disposed in registry with the cen- 10 trally disposed end plate.
3. An oil cleaner including a plurality of spaced parallel plates, said plates having cir- 15 cumferentially spaced axially disposed oil passages, the intermediate and one of the outer end plates each being centrally aper- tured, said plates mounted for rapid rotation on a substantially horizontal axis, a station- 20 ary casing enclosing said plates having an eccentric oil inlet adjacent the non-centrally apertured end plate and having a concentric oil outlet disposed in registry with the cen- 25 trally disposed end plate and a settling basin communicating with the lower end of and disposed below said casing, said settling basin having a removable drain plug at its lower end.
4. An oil cleaner including a plurality of spaced parallel plates, said plates having cir- 30 cumferentially spaced axially disposed oil passages, the intermediate and one of the outer end plates each being centrally aper- tured, said plates mounted for rapid rotation on a substantially horizontal axis, a station- 35 ary casing enclosing said plates having an eccentric oil inlet adjacent the non-centrally apertured end plate and having a concentric oil outlet disposed in registry with the cen- 40 trally disposed end plate and a settling basin communicating with the lower end of and disposed below said casing, said settling basin having a removable drain plug at its lower end, said drain plug having a drain cock.
5. An oil cleaner including a plurality of spaced parallel plates, said plates having cir- 45 cumferentially spaced axially disposed oil passages, the intermediate and one of the outer end plates each being centrally aper- tured, said plates mounted for rapid rotation on a substantially horizontal axis, a station- 50 ary casing enclosing said plates having an eccentric oil inlet adjacent the non-centrally apertured end plate and having a concentric oil outlet disposed in registry with the cen- 55 trally disposed end plate and a conduit leading from the casing outlet to the parts to be lubricated.
6. An oil cleaner including a plurality of spaced parallel plates, said plates having cir- 60 cumferentially spaced axially disposed oil passages, the intermediate and one of the outer end plates each being centrally aper- tured, said plates mounted for rapid rotation on a substantially horizontal axis, a station- 65 ary casing enclosing said plates having an eccentric oil inlet adjacent the non-centrally apertured end plate and having a concentric oil outlet disposed in registry with the cen- 70 trally disposed end plate.
7. An oil cleaner including a plurality of spaced parallel circular plates having thick- 75 ened peripheries spaced apart a distance less than the spacing of the major portion of the plates, means mounting said plates for rapid rotation on a substantially horizontal axis, said plates having circumferentially spaced axially disposed aligned oil passages, the intermediate and one of the endmost plates each being centrally aper- 80 tured, a stationary casing enclosing said plates having an eccentric oil inlet adjacent the non-centrally apertured end plate and having a concentric oil outlet disposed in registry with the cen- 85 trally apertured end plate.
8. In a centrifugally operated cleaner, a battery of circular plates having thickened peripheries, means securing said plates together in spaced parallel relation, all of said plates having a series of aligned circumferentially spaced apertures, one of said end plates and the remaining intermediate plates 90 having aligned central apertures, a casing having an eccentric intake adjacent the non-centrally apertured plate and having a concentric outlet conduit extending through the opposite side and into the centrally apertured 95 end plate.
9. In a centrifugally operated cleaner, a battery of circular plates having thickened peripheries, means securing said plates together in spaced parallel relation, all of said plates having a series of aligned circumferentially spaced apertures, one of said end plates and the remaining intermediate plates 100 having aligned central apertures, a casing having an eccentric intake adjacent the non-centrally apertured plate and having a concentric outlet conduit extending through the opposite side and into the centrally apertured 105 end plate and means for mounting and rapidly rotating said plate assemblage on a sub- 110 stantially horizontal axis within said casing.
10. In a centrifugally operated cleaner, a battery of circular plates having thickened peripheries, means securing said plates together in spaced parallel relation, all of said plates having a series of aligned circumferentially spaced apertures, one of said end plates and the remaining intermediate plates 115 having aligned central apertures, a casing having an eccentric intake adjacent the non-centrally apertured plate and having a concentric outlet conduit extending through the opposite side and into the centrally apertured end plate, means for mounting and rapidly rotating said plate assemblage on a sub- 120
- 60 125
- 65 130

stantially horizontal axis within said casing and a settling basin communicating with the lower end of and disposed below said casing.

11. In a centrifugally operated cleaner, a battery of circular plates having thickened peripheries, means securing said plates together in spaced parallel relation, all of said plates having a series of aligned circumferentially spaced apertures, one of said end plates and the remaining intermediate plates having aligned central apertures, a casing having an eccentric intake adjacent the non-centrally apertured plate and having a concentric outlet conduit extending through the opposite side and into the centrally apertured end plate, means for mounting and rapidly rotating said plate assemblage on a substantially horizontal axis within said casing and a settling basin communicating with the lower end of and disposed below said casing having a drain outlet at its lower end and a removable closure plug therefor.

12. An oil cleaner including a plurality of spaced parallel plates, said plates having circumferentially spaced axially disposed oil passages, the intermediate and one of the outer plates being centrally apertured, a stationary casing enclosing said plates and within which the same is mounted for rapid rotation, said plates having an eccentric oil inlet adjacent the non-centrally apertured end plate and having a concentric oil outlet disposed in registry with the centrally disposed end plate.

13. In a centrifugally operated fluid cleaner, a battery of circular plates, a stationary casing enclosing the same and within which said plate battery is mounted for rotation on a concentric axis, said plates having a series of aligned circumferentially spaced apertures, one of said end plates and the remaining intermediate plates having aligned central apertures, said casing having an eccentric intake adjacent the non-centrally apertured end plate and having a concentric outlet extending through the casing and into the centrally apertured end plate and a settling basin communicating with the lower end of and disposed below said casing.

CHARLES HOCHSTATTER.
